H. VALLOS

PAPER HANGER

Filed March 26, 1923

INVENTOR.
BY Harry Vallos

Thomas S. Donnelly
ATTORNEY.

UNITED STATES PATENT OFFICE.

HARRY VALLOS, OF DETROIT, MICHIGAN.

PAPER HANGER.

Application filed March 26, 1923. Serial No. 627,775.

To all whom it may concern:

Be it known that I, HARRY VALLOS, a citizen of the United States, and a resident of Detroit, in the county of Wayne and State 5 of Michigan, have invented a new and useful Improvement in a Paper Hanger, of which the following is a specification.

My invention relates to a new and useful improvement in a paper hanger and has for 10 its object the provision of mechanical means for hanging paper so as to eliminate the necessity for the use of a platform or ladder during the hanging of the paper.

Another object of the invention is the provision of a paper hanger having means for holding the end of the paper until the same is placed in position against the surface to which it is to be attached and means for releasing the same at the will of the operator.

Another object of the invention is the provision in a paper hanger of means for automatically putting the paste on the paper as it is used or shortly before it is used.

Another object of the invention is the provision of a paper hanger having a presser roller and a paste affixer adjustable relatively to each other.

Another object of the invention is the provision in a paper hanger of a paste container 30 and automatic means for feeding the paste from the container to a paste affixer as the paste is used.

Other objects will appear hereinafter.

The invention consists in the combination 35 and arrangements of parts hereinafter described and claimed.

The invention will be best understood from a reference to the accompanying drawings which form a part of this specification 40 and in which,

Fig. 1 is a top plan view of the invention,

Fig. 2 is a side elevational view of the invention,

Fig. 3 is a fragmentary elevational view 45 taken on substantially line 3-3 of Fig. 2, and

Fig. 4 is an elevational view showing the closure for the paste affixer used in the invention.

The invention is adapted for use in hanging paper on the walls and ceilings of rooms and for hanging posters and the like.

The invention in its preferred form comprises a U-shaped frame 7, to the central portion of which is attached a suitable handle. Mounted in holes formed in the legs of the

U-shaped member is a rod 9 upon which is mounted fixedly a roll of paper so arranged that when the end of it is pulled the roll and the rod will turn to unwind the paper. The 60 legs of the U-shaped member have an angularly turned portion 11, and mounted upon the legs of the U-shaped portion, adjacent the point where the same are bent, is a paste container 12, having the portion 13, flattened 65 and perforated to allow the paste to exude therefrom onto the paper passing over it. Communicating with the member 12 are pipes 14, 15 and 16 which communicate with a pipe 18 which is fastened to a rubber tube 70 17, a suitable control valve being interposed in the tube 17. The tube 17 is in communication with a tank or paste container 19 which is provided with a cover 20, which is threaded thereon, said cover being provided 75 with a dome 21 in which one end of the tube connects and through which projects a stem 24, the inner end of which is attached to a disk 22 which is positioned within the tank loosely, and rests upon one end of a 80 spring 23, the other end of which engages the bottom of the tank. An opening is formed in the cover and is provided with a cap 25 which serves as a closure for the opening. The paste is deposited in the tank 85 through the opening, the disk being first pressed downwardly toward the bottom of the tank against the pressure of the spring. When the paste is deposited in the tank and the cap placed in position the pressure may 90 then be released from the stem 24 and the spring will then have a tendency to move the disk upwardly of the tank thus forcing the paste through the tube 17 and through the pipes 18, 14, 15 and 16 into the paste 95 distributor 13, from which it may escape through the perforations formed in this member.

Cooperating with the legs of the U-shaped member are bars 26 and 26', each of which 100 is bifurcated at its end 27 and adapted to straddle respectively a bolt 28 and 28', cooperating with said bolts being suitable wing nuts 29 and 29'. Journaled in openings formed in the bars 26 and 26' is a rod 105 30 upon which is mounted a roller 31, which is preferably made of rubber, or some other suitable material for pressing the paper against the wall or other surface to which it is to be attached. Mounted on the bars 110 26 and 26' is a lug 32, provided with an abutment stop or shoulder 33. Projected

through the lug and curled around the same is one end 34 of a wire holding member, which is adapted to engage the shoulder 33 upon an attempt to turn the member 34 in 5 the lug 32. The member 34 connects with the leg of a U-shaped member in which is formed the coil 35 to give a spring effect to the member, the bight 36 of the U-shaped member being adapted to normally engage 10 the rubber roller 31.

When it is desired to use the device the paper is unwound from the roll 10 and drawn over the member 12 and under the roller 31 and placed between the roller 31 15 and the bight 36. As the paper passes over the portion 13 of the paste affixer 12 the necessary amount of paste adheres to the paper. When the roller 31 is placed against the wall at the proper position the bight 36 20 may be drawn free from the roller by means of a cord or other suitable means, thus allowing the paper to engage at its end the wall or other surface to which it is to be affixed. The bight is then restored to its 25 normal position and as the roller is drawn along the surface to be papered the paper is drawn from the roll and the proper amount of paste placed thereon and the same is then pressed firmly against the surface 30 to be papered the paste causing it to adhere in position. When the particular strip is finished the operator then cuts the strip from the roll by any suitable means, the point of severing being beyond the 35 rubber roller, so that the device may then be used to cover another strip of the surface.

As the paper is drawn from the roll the marginal trimming is performed by suitable cutting members mounted on the legs in 40 which the rod 9 is journaled. The bight of a U-shaped member 37 is mounted on each of the legs in which the rod 9 is journaled and rotatably mounted on the legs 38 and 45 39 are disks 40 and 41, which are provided with sharpened peripheries and spaced apart just sufficiently to allow the paper to be drawn between them so as to sever the marginal edge of the paper from the main body thereof. If it is desired to sever only 50 one marginal edge from the paper only one of the cutting sets will be necessary.

By mounting the rubber roller on bars which are adapted for adjustment at their 55 bifurcated end the position of the roller 31 may be adjusted relatively to the roller 10, so that the most efficient position may be used when papering the walls and when papering the ceiling. When the adjustment has been made the wing nuts are tightened 60 to retain the parts in the desired position.

While I have illustrated and described the preferred form of structure I do not wish to limit myself to the precise form of structure shown but desire to avail myself of such variations and modifications as come 65 within the scope of the appended claims.

Having thus described my invention what I claim is:

1. A paper hanging machine comprising a paste container having an open top; a 70 spring positioned in said container and adapted for engaging, at one end, the inner surface of the base of said container; a disk mounted in said container and adapted for engaging at its under surface, the opposite 75 end of said spring; a cover for said container; a stem mounted on said disk and projecting outwardly from said cover, said container being adapted for containing paste between said disk and said cover; a 80 tube connected to said cover and communicating with the interior of said container; a frame, a paste distributor mounted in said frame and communicating with said tube; a presser roller mounted on said frame; and a 85 paper roller mounted on said frame.

2. A paper hanging machine comprising a paste container; a frame; a paste distributor mounted on said frame; means for delivering paste from said container to said 90 distributor; a roller mounted on said frame for supporting a roll of paper; a presser roller mounted on said frame, said paste distributor being intermediate said rollers; and a U-shaped clamping member mounted 95 on said frame, adjacent said presser roller and adapted for engaging, at its bight, said presser roller, for retaining a strip of paper in fixed relation to said presser roller.

3. A paper hanging machine comprising 100 a paste container; a frame; a paste distributor mounted on said frame; means for delivering paste from said container to said distributor; a roller mounted on said frame for supporting a roll of paper; a presser roller mounted on said frame, said paste distributor being intermediate said rollers; and a U-shaped clamping member mounted 105 on said frame, adjacent said presser roller and adapted for engaging, at its bight, said presser roller, for retaining a strip of paper in fixed relation to said presser roller; and resilient means for normally retaining 110 said bight in engaging position with said roller.

In testimony whereof I have signed the foregoing specification.

HARRY VALLOS.
